UNITED STATES PATENT OFFICE.

LAWRENCE E. CONNELLY, OF CLEVELAND, OHIO.

CLEAN-OUT FLUE FOR WATER-TUBE STEAM-GENERATORS.

1,200,922.

Specification of Letters Patent. Patented Oct. 10, 1916.

Application filed May 6, 1916. Serial No. 95,929.

To all whom it may concern:

Be it known that I, LAWRENCE E. CONNELLY, a citizen of the United States, residing at Cleveland, in the county of Cuyahoga and State of Ohio, have invented certain new and useful Improvements in Clean-Out Flues for Water-Tube Steam-Generators; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention relates to steam generators, and especially to water tube steam generators wherein there are pockets between the baffle walls and the side walls of the boiler setting, in which soot and dust will accumulate; and it consists in providing a flue through which said soot and dust may be conveyed into the chamber behind the fire-wall of the boiler setting.

The features of my invention are herein-after fully described and pointed out, and are illustrated in the accompanying drawings, in which:—

Figure 1, is a vertical section of the boiler setting with a water tube steam generator in place therein, showing my invention installed therein. Fig. 2, is a transverse section of a fragment of the same, showing an edgewise view of my invention. Fig. 3, is a side view of my soot flue removed from the boiler setting.

In these drawings A, indicates a mud drum, and A', A'', and A''', indicate the upper drums of the water tube boiler, which drums are connected by water tubes B, B', B'', B''' and B'', and which is installed in the usual boiler setting C, and is provided with baffle walls D, D', D'' and D''', which baffle walls are continuous from side to side of the boiler setting: there is, therefore, between the baffle walls D' and D''', a pocket having the drum A, as the bottom thereof, in which dust and soot accumulate.

One end of the drum A, and preferably embodied in one of the side walls, C, I place a hollow segmental flue E, having an opening E', in the wall thereof, adjacent to the water tubes B'. The lower end of the flue E, is provided with a door E'', which is hinged to the body of the flue E, and is provided with a rod F, which extends outwardly

through the rear wall of the boiler setting, where it is provided with a handle F', by means of which the rod F, may be rotated to open the door E'', when it is desired to clean out the soot and ashes from the pocket between the baffle walls D' and D''. At the opposite side of the boiler setting C, I provide a door G through which a steam "lance" may be inserted when it is desired to blow the soot and ashes off of the drum A, and into the flue E.

In operation when it is desired to clean the ashes off of the drum A, the handle F' is operated to open the door E''; and while the door E'', is open, a steam lance or other suitable tool may be inserted through the door G, and the ashes forced into the opening E', of the flue E, and thence through the flue into the chamber under the drum A, when the door E'', can be again closed, and the ashes and soot removed through the door H, in the rear wall of the boiler setting, when desired. The door E'', at the lower end of the flue E', prevents the by-pass of the furnace gas from the space between the baffle walls D' and D'', and likewise prevents the passage of cool air from the rear chamber into said space.

While I have shown my invention as applied to the water tube boiler in which there is but one pocket, wherein ashes may accumulate, it is obvious that the opening E', may be made sufficiently extensive to receive ashes from more than one pocket above the drum A, without departing from the scope of my invention.

Therefore, having described the construction and operation of my invention, so as to enable others to utilize the same, what I claim as new and desire to obtain by Letters-Patent, is:—

1. The combination in a water tube boiler, of a lower drum, a plurality of baffle walls in spaced relation to each other and extending upwardly from said drum, a flue at one end of said drum communicating with the space between said baffle walls and terminating behind said drum, and means to close the exit end of said flue, substantially as described.

2. The combination in a water tube boiler, of a lower drum, a plurality of baffle walls in spaced relation to each other and extending upwardly from said drum, side walls closing the spaces between the edges of said baffle walls, a segmental flue embedded in one of

said side walls around said drum, and having
an opening which communicates with the
space between said baffle-walls, and an open-
ing which communicates with a chamber be-
hind said drum, and means to open and
close the last mentioned opening, substan-
tially as described.

3. The combination in a water tube boiler,

of a series of baffle walls in spaced relation,
a transverse fire-wall, and a clean-out flue **10**
communicating with the space between said
baffle-walls and the chamber behind said fire-
wall, substantially as described.

In testimony whereof I affix my signature.

LAWRENCE E. CONNELLY.
